Atty.

UNITED STATES PATENT OFFICE.

JAMES H. MARCHANT, OF SCHENECTADY, NEW YORK.

AUTOMATIC FIRE-ALARM.

No. 837,941.

Specification of Letters Patent.

Patented Dec. 11, 1906.

Application filed April 20, 1906. Serial No. 312,783.

To all whom it may concern:

Be it known that I, JAMES H. MARCHANT, a citizen of the United States, residing at Schenectady, county of Schenectady, and State of New York, have invented certain new and useful Improvements in Automatic Fire-Alarms, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 of the drawings is a plan view of my improved automatic fire-alarm circuit-closer, showing the contacts held apart from each other by means of the fusible block. Fig. 2 is a side view of the same. Fig. 3 is a plan view showing the contacts in engagement with each other. Fig. 4 is a cross-section taken on the broken line 4-4 in Fig. 1.

The principal object of the invention is to provide a simple and reliable device for automatically closing a fire-alarm electric circuit when subjected to a temperature indicative of danger from fire.

Referring to the drawings, wherein the invention is shown in its preferred form, 1 represents a base of insulating material adapted to be secured to a wall or ceiling by screws inserted through the screw-holes 2, upon which insulating-base are mounted a pair of posts 3 and 4, which project through said base and have their ends, which project rearwardly of the base, adapted to be connected with the wires 5 and 6 of opposite polarity of an electric fire-alarm system, which may be of any known kind.

The posts 3 and 4 are of conducting material, preferably metal, and are adapted to be electrically connected together by means of a circuit-closing spring-plate 7, mounted at one end upon the post 3 and having its other end adapted to yieldingly engage the other post 4 to close the circuit.

When there is no occasion for the circuit to be closed, it is maintained open, with the circuit-closing plate 7 held out of contact

with the post 4 by means of a fuse-block 8, interposed between said circuit-closing plate 7 and a post 9, erected from said base 1, the length of the fuse-block 8 being such that when interposed between said post 9 and circuit-closing plate 7 the latter will be held at a sufficient distance from the post 4 to interrupt the electrical circuit.

The fuse-block 8 may be made of any easily-fusible material adapted to the requirements of the system. A block made of paraffin or a mixture of paraffin is well adapted for the purpose. When the temperature reaches a sufficiently high degree to melt or soften the fuse-block 8, the resilient force of the spring-plate 7 will cause it to make contact with the post 4 to complete the circuit and operate the alarm apparatus. Devices of this general character are commonly attached to vertical walls or overhead walls or ceilings, and unless the fuse-block be locked in position securely it is liable to be accidentally displaced by vibration and other causes and result in the sounding of a false alarm. To prevent such accidents, I provide the post 9 and the circuit-closing plate 7 with seats or holders for the opposite ends of the fuse-block, the seat in the post 9 being formed by a recess 10 and the seat in the plate 7 being formed by a recess 11 in the boss 12 in the plate. When the opposite ends of the fuse-block are seated in the respective recesses 10 and 11, the block is locked securely in position and cannot be jarred or shaken out of place. As shown in the drawings, the spring-plate 7 is an approximately straight piece of resilient sheet metal, one end of which is secured in a slot in the upper end of the post 3, and the fuse-block seat is formed on the plate 7 by means of a separate block, soldered or otherwise secured thereto, as shown in Fig. 4. I am thus able to secure maximum strength and durability with a minimum amount of metal in said spring-plate.

What I claim as new, and desire to secure by Letters Patent, is—

A circuit-closer for electric fire-alarm systems comprising a slotted post connected with one branch of the electric circuit; a spring-plate secured in the slot in said post; a boss mounted upon said spring-plate, and provided with a seat for one end of a fuse-

2
block; a contact-post connected with the other branch of the electric circuit, and located in the path of said spring-plate; a resisting support provided with a seat for the other end of said fuse-block; and a fuse-block interposed between said resisting support and spring-plate with its opposite ends located in said respective seats and adapted

to hold said spring-plate out of contact with said contact-post.

In testimony whereof I have hereunto set my hand this 14th day of April, 1906.

JAMES H. MARCHANT
